TOILET VENTILATOR

Filed April 16, 1936

UNITED STATES PATENT OFFICE

2,072,493

TOILET VENTILATOR

William Beard, Colorado Springs, Colo.

Application April 16, 1936, Serial No. 74,738

2 Claims. (Cl. 4—213)

This invention relates to ventilators and more particularly to an attachment which may be secured to a conventional toilet bowl for ventilation thereof.

5 An object of this invention is to provide a device of this kind which can be readily applied to the present construction of a toilet bowl without altering any of the construction of the bowl proper so as to provide a means for ventilation 10 thereof.

Another object of this invention is to provide an improved fan and motor therefor, together with a connection between the fan and the intake portion thereof so that the fan and motor 15 can be mounted in any desired position with respect to the toilet bowl, thus making it unnecessary to change the present construction of the bowl or any of the parts associated therewith.

A further object of this invention is to provide 20 an improved motor operating switch which is adapted to be embedded in the seat for the bowl and which is so mounted that the operating parts thereof will not be exposed.

The above and various other objects and advantages of this invention will in part be described in, and in part be understood from the following detail description of the present preferred embodiment, the same being illustrated in the accompanying drawing, wherein:—

30 Figure 1 is a fragmentary side elevation of a conventional toilet bowl having a ventilating means, constructed according to an embodiment of this invention, mounted thereon.

Figure 2 is a top plan of the bowl and ventilating attachment.

Figure 3 is an enlarged fragmentary sectional view taken on the line 3—3 of Figure 2.

Figure 4 is a fragmentary sectional view taken substantially on the line 4—4 of Figure 2.

40 Figure 5 is a fragmentary sectional view taken substantially on the line 5—5 of Figure 2.

Figure 6 is a sectional view taken on the line 6—6 of Figure 2.

Referring to the drawing wherein like symbols 45 designate corresponding parts throughout the several views, the numeral 10 designates generally the rim portion of a bowl B of conventional construction which is provided with a seat 11 hinged to the rear portion 12 of the rim or top 50 10 by a conventional hinge structure 13. This toilet bowl and seat structure is conventional and it will be understood that the hereinafter described ventilating means may be secured to any of the present bowl and seat constructions 55 at present in use.

In order to provide a means whereby the interior of the bowl B may be ventilated, I have provided a fan, generally designated as 14, having an outlet 15 and an intake pipe 16 connected to the central portion thereof. This fan 14 is operated by a motor 17 which is connected as by a conductor 18 to a suitable source of electric current supply.

An intake manifold 19 is disposed on the rear portion or table 12 of the rim 10 and is connected 10 to the intake pipe 16 of the fan 14 and this intake manifold 19 is secured to the table portion 12 of the bowl B beneath the securing bolts for the hinge 13 of the seat 11. The manifold 19 comprises a relatively flat intake nozzle 20 which 15 is adapted to extend beneath the pintle 21 of the hinge structure 13 with the open or forward end thereof confronting the interior of the bowl B.

The rear portion of the nozzle 20 communicates with a transversely extending pipe 22 and 20 this pipe 22 is provided at opposite ends thereof with an annular seat portion 23. These seat portions 23 are of identical construction so that the reduced end portion 24 of the intake pipe 16 may be connected to either end of the manifold 25 pipe 22. A plug or cap 25 is adapted to be secured to one end of the manifold pipe 22 by means of a threaded rod 26 which engages at one end in a boss 27 provided on the inside of the intake pipe 16. A base plate 27 is formed integral 30 with the nozzle 20 and the pipe 22 and is provided with suitable openings to receive the bolts for securing the hinge structure 13 to the rear or table portion 12 of the rim 10. The end of the intake pipe 16 which engages the fan structure 35 14 is provided with an annular flange 28 engaging in a recess 29 provided in one side portion 30 of the fan housing. The bolts or screws 31 extend into the housing portion 30 and overlie the outer side portion of the flange 28 so as to firmly 40 hold this flange in the seat 29. The opposite side portion 32 of the fan housing is also provided with a recess 33 to receive a flange 34 carried by a mounting means 35 for attaching the fan housing to one side of the motor 17.

The fan blades 36 are secured to a hub 37 which is attached as by a set screw 38 to the driving shaft 39 of the motor. Preferably, these blades 36 are so constructed that the fan may be turned in either direction without effecting the flow of 50 air through the housing. The flange 34 is secured as by bolts 40 in the annular recess 33 and this recess 33 is substantially the same size as the recess 29 so that the fan housing may be reversed if desired.

The outlet member 15 of the fan housing, as shown in Figures 1 and 2, may be connected to a suitable carry-off means and, in the present instance, this outlet connection 15 discharges 5 through a wall 41 so that the air discharged through this connection 15 will flow upwardly in the space between the wall or the connection 15 may be connected to a ventilating pipe, where such is available.

10 The seat 11 is sealed with respect to the rim 10 by means of a yieldable sealing member 42 in the form of one or more strips of sponge rubber, or the like, which are adapted to be attached by any suitable attaching means to the underside 15 of the seat 11. Preferably, the cushioning means 42 is cut away, as at 43, so as to receive the intake nozzle 20 and the forward portion of the cushioning means 42 is also cut away so as to admit air into the bowl B.

20 The motor 17 is set in operation by means of a switch structure which is carried by the seat 11 and this switch structure comprises a housing 44 which is inserted in an opening 45 provided in the seat 11 and, preferably, the housing 44 25 is round in transverse section so that a hole may be bored into the seat 11 from the rear thereof to snugly receive the housing 44. A fixed contact member 46 is carried by an insulating body 47 within the housing 44 and a yieldable contact 30 48 is also carried by this insulating means 47 and disposed in confronting relation to the fixed contact or terminal 46. The contact 46 is connected to a wire or conductor 49 and the movable contact 48 is connected to a wire 50 extending 35 through a cable 51 and these two conductors 49 and 50 are interposed in the conductor 18 which supplies current to the motor 17.

The movable conductor 48 is moved into contacting relation with a fixed contact 46 by means 40 of a plunger 52 which is loosely mounted in an opening 53 provided in the seat 11. This opening 53 extends vertically and opens through the underside of the seat 11 so that the lower end of the plunger 52 will contact with the upper surface 45 face of the exposed portion of the sealing member 42. In this manner, when pressure is applied to the seat 11, that portion of the cushioning member 42 extending across the lower end of the opening 53 will be distorted upwardly so that 50 the plunger 52 will be moved in an upward direction and thereby force the movable terminal or contact 48 into circuit closing position.

In the use and operation of this ventilating means, the manifold 19 is adapted to be fixedly 55 secured beneath the bolts for the hinge structure 13 and the cushioning means 42 attached to the underside of the seat 11. The conductor 18 is connected to a suitable source of current supply and the motor 17 and the fan 16 may be mounted 60 on the desired side of the bowl B and in the desired position with respect to the bowl B through the use of the reversible coupling means 23 and 24 carried by the manifold 19 and the intake pipe 16 respectively. When the seat 11 is 65 not occupied, the cushioning member 42 will not be under pressure and the plunger 52 will, therefore, not maintain the movable contact 48 in circuit closing position. However, when pressure is applied to the seat 11, the cushioning member 70 42 will force the plunger 52 upwardly to close the circuit to the motor 17, so that during the entire time that pressure is applied to the seat 11, the motor 17 will be operated and air drawn 75 out of the bowl B through the front portion of

the bowl at which point the cushioning member 42 is split.

This ventilating attachment is exceedingly simple in construction and is rendered practical by reason of the fact that the attaching means for the fan and motor may be reversed so that the outlet for the fan 16 may be connected to a suitable source of carry-off means and the motor and fan may be disposed in an inconspicuous position. While, in Figure 1, the intake pipe 16 10 is disposed on an angle to the vertical, it will be understood that by reason of the adjustable connection 23—24 between this intake pipe 16 and the manifold pipe 22, the relation of this intake pipe 16 to the bowl B or to the outlet means 15 for the air may be adjusted in any desired angle, thus making it unnecessary for a dealer to maintain right and left connections for the motor and fan and making it possible for the device to be quickly attached to any of the present constructions of toilet bowls and seats.

In Figure 1, the outlet 15 of the fan housing 14 is shown in a substantially horizontal position and the dotted line showing in this figure indicates a second position of this outlet 15. By 25 reason of the connection between the housing 14 and the motor 17 this fan housing 14 may be adjusted so as to dispose the outlet 15 in any desired position depending only on the means available adjacent the toilet bowl B for carrying off the air withdrawn from the bowl. The adjustability of the outlet 15 of the fan makes the installation of the ventilator an exceedingly simple matter so that a plumber or other mechanic may easily mount the ventilator on the 30 toilet bowl and connect the outlet portion of the fan with whatever means is available at the installation for carrying off the air discharged through the outlet 15.

In many of the installations at present available for ventilating toilet bowls, it is necessary to provide special means for carrying off the air and, in addition, special types of bowls and seats are necessary, whereas with the present invention, the device may be attached to the present construction of a toilet bowl and seat and it is not necessary to use a separate pipe for the air discharged through the outlet side of the fan as this outlet may be connected to a carry-off pipe or it may be connected to the wall or floor construction where either one of these constructions are of a character to permit the flow of air therethrough. Where the outlet 15 is connected directly to the wall between a pair of joists it 55 is only necessary to cut one or more holes in the plate at the top of the wall studding so that the air may readily pass through the holes into the atmosphere.

I claim:—

1. In combination, a toilet bowl, a seat hingedly secured to the top thereof and a ventilating means connected to the bowl, said ventilating means comprising a suction fan, a motor, means for connecting said motor to either side of the fan, a suction nozzle interposed between the rear portion of the seat and the top of the bowl, a pipe carried by the nozzle and extending laterally of each side thereof, an intake pipe connected at one end to a side of the fan opposite from said motor, means for reversibly connecting the intake pipe to a selected end of the first named pipe, means for closing the end of the first named pipe opposite from the intake pipe, a switch connected to the motor, means for mount- 70 75 80 85 90 95 98 99

ing the switch within the seat adjacent the rear portion thereof, a yieldable sealing member interposed between the seat and the rim of the bowl, and a switch operating member interposed 5 between the sealing member and the switch whereby to close the switch upon compression of the sealing member.

2. A ventilating means for a toilet bowl provided with a seat comprising an intake manifold 10 adapted to be interposed between the seat and the rim of the bowl, a pipe connected interme-

diate its ends to the manifold and extending laterally of each side thereof, said pipe having open opposite ends, an intake pipe connected at one end to a selected end of said first pipe, means closing the opposite end of said first pipe, 5 a fan connected to the opposite end of said intake pipe, a motor for said fan, a yieldable sealing member interposed between said seat and the rim of the bowl, and a switch connected to said motor.
